UNITED STATES PATENT OFFICE

PAUL KÄPPLER, OF DRESDEN, GERMANY

KEY-ACTION DEVICE FOR TYPEWRITING MACHINES

Application filed October 20, 1927, Serial No. 227,393, and in Germany November 27, 1926.

The invention relates to typewriting machines having an obliquely arranged type bar bearing segment and in which each key lever is guided by a pair of substantially parallel 5 links, the lower link, by means of an upright arm transmitting the motion to the type bars through connecting rods.

This invention has for its object to obtain a particularly compact construction of such 10 machine, with economy of the parts required and easy assembly, which is an advantage for quantity production.

It is known, in such machines, to bring the connecting rods which actuate the type 15 bars close to the latter, so that a space is left between the rods and the upright arm of the link. This space has heretofore not been utilized. With the known machine, moreover, the link bearing is bent, which gives 20 rise to unsatisfactory leverage.

According to the present invention, the universal bar and the extensions of the lower link arm which drive the universal bar are accommodated in the aforesaid space. In 25 order to obtain better freedom of movement with this arrangement, the axle of the lower link is also made straight, which carries with it further advantages. The manufacture and assembly is simplified and uniform angular 30 movements and equal lengths of the link levers are also obtained. This is an advantage in quantity production. This also simplifies overcoming the lateral distance between the link bearings and the plane of 35 movement of the type bar, it being only necessary for this purpose to correspondingly bend the upright arm to one side. It is then only necessary to bend the two ends of the connecting rods away from each other so 40 that they move about intersecting axes. This bending of the ends of the connecting rods does not give rise to any inconvenience. The utilization of space is also aided by the fact that the upper link pivot is not exactly vertically situated above the lower link pivot, but 45 is set forward sufficiently to leave room between the upper pivot and the position of the upright arm in striking position, for accommodating a cross-connection for the spacing 50 key levers. Consequently, the upper link is

shorter than the lower link. This is of no consequence as regards guiding the keys, which still describe an almost vertical movement parallel to one another, whereas even with typewriting machines having very long 55 key levers, one has to allow for an obliquity of about 5% in the striking position.

A machine constructed according to the present invention only requires the upper and lower links (which are mounted on two straight pivots) as the intermediate elements for transmitting the movement from the keys to the type bars, the connecting rods and suitably positioned return springs. The lower links are shaped to form both the universal 60 key levers and the upright arms.

The accompanying drawing illustrates a constructional example of a typewriter according to my invention.

Fig. 1 is a longitudinal sectional view of 70 the machine.

Fig. 2 is a plan view of one of the outer type bars and relative parts.

Fig. 3 is a view looking from the rear toward some of the parts shown in Fig. 2. 75

Fig. 4 is a sectional plan view of part of the machine on one side of its longitudinal center line $x-x$.

Fig. 5 is a view showing a detail of construction. 80

The keys 1, 2, 3 and 4 are connected above to a link 5 and below to a link 6, which forms one arm of an intermediate lever 7. The keys are thus guided in an almost straight path. The links 5 and 6 are mounted on rods or pins 8 and 9. These are inserted in the bearing bracket 10 of the machine frame 11, the bracket 10 being slotted in known manner to receive and guide the links. The pin or rod 8 is set further forward than the pin or rod 9. 85

The keys 1-4 all have an equal downward movement. Consequently, they all describe the same angle of movement, so that arms 12 on the levers 7, through which the universal bar 13 is driven all make the same angular movement. Thus the parts driven from the universal bar 13, i. e., the carriage escapement mechanism, the ribbon feed and ribbon shift motion, are all actuated in exactly the same manner by every one of the keys. 95 100

The intermediate lever 7 forms the upright arm of a three-armed lever including the link 6 and arm 12. The arms 7 transmit motion to the type bars 15 through connecting rods 14. The different travel due to the various heights and inclinations of the type bars is compensated by corresponding variations of the lengths and lateral bending of the arms 7, as seen in Fig. 2. When the keys 5 are depressed, the arms 7 stand almost upright. Between the bearing bracket 10 and the arms 7 there is still room for the channeled cross bar 16 of the spacing lever 19, owing to the forward position of the pivot 8. The spacing lever 19 through the arms 18 fulcrumed on rod 8, and each having a lug 18' engaging the channel in bar 16, actuates arms 20 arranged alongside the upper ends of the arms 7. These act upon rollers 45 of 10 arms 21 rotatable on a shaft 22, which arms 21 carry the universal bar 13, so that depression of the lever 19 will bring the universal bar 13 into the dotted position, thereby actuating the carriage escapement. The connecting rods 14 lie close to the type bars 15 so that there is only just space between them for the return springs 17. The universal bar 13, by its movement, fills the remaining space 15 between the two arms 7 and 12. The available space is thus utilized to the fullest possible extent.

Having now particularly described and ascertained the nature of my said invention and in what manner the same is to be performed, I declare that what I claim is:—

1. In a typewriter of that kind having an obliquely arranged type bar bearing segment, the combination with the type bars, of type bar actuating key levers and a spacing key lever, a pair of parallel motion link members coupled to each key lever and pivoted one above the other upon horizontal transverse axes to the machine frame, the lower link member being longer than the upper link member and having an extension arm projecting horizontally in rear of its pivot and carrying a substantially vertical arm, a universal bar disposed in the angle between said horizontal and vertical arms of the lower link members so as to overlie the horizontal arms of said link members for movement thereby in one direction upon the depression of the respective key levers, connecting rods underlying the bank of type bars 20 and connecting the vertical arms of the lower link members with the type bars, rocker arms carrying the universal bar arms for actuating said rocker arms, and a connecting member between said actuating arms operatively connected to the spacing lever, said connecting member being movable in the space between the upper links of the group of parallel motion links and the vertical arms of the lower links of said group.

2. A typewriter of the character set forth

in claim 1, wherein an inclined bracket is provided to carry the pivots of the parallel motion links and wherein the pivots of the upper links of the parallel motion links carried by said bracket are arranged closer to the front of the machine than the pivots for the lower links of the parallel motion links carried by said bracket, so as to provide increased space between the first-named pivots and the vertical arms of the lower link extensions for the movement of the connecting member between the actuating arms which transmit motion from the space key to the universal bar.

3: A typewriter of the character set forth in claim 1 wherein the type bar connecting rods and the arms coupled to the universal bar are connected by return springs to the type bar bearing segment, which springs are disposed in the space between said rods and arms and the overlying type bars.

4. A typewriter of the character set forth in claim 1 wherein the axes of the upper and lower link members are straight and parallel, and the lower link members of the parallel motion links and their horizontal extension arms are of like shape and length while their vertical extension arms are of varying lengths and bent laterally to varying degrees with relation to the vertical plane of the horizontal arms of said link members, to allow for the proper plane of travel of each type bar.

5. A typewriter of the character set forth in claim 1 wherein the pivotal support for the upper and lower link members of the parallel motion links is straight and the pivotal support for the lower link member is arranged in a vertical plane in rear of the vertical plane of the pivotal support for the upper link member.

PAUL KÄPPLER.
